VERA F. LANGTON AND JAMES J. UNDERWOOD, OF NEW YORK, N. Y.

PRINT-WASHING DEVICE.

1,417,077.

Specification of Letters Patent. Patented May 23, 1922.

Application filed July 8, 1915, Serial No. 38,825. Renewed October 19, 1921. Serial No. 508,829.

To all whom it may concern:

Be it known that we, VERA F. LANGTON, a subject of the King of England, residing in the city, county, and State of New York, and JAMES J. UNDERWOOD, a citizen of the United States, residing in the city, county, and State of New York, have invented certain new and useful Improvements in Print-Washing Devices, of which the following is

10 a specification.

Our invention relates to a sheet handling device of general application and particularly relates to a device for supporting a plurality of wet sheets while subjecting the 15 same to a washing, drying or other treatment incidental to the finishing of flexible photographic films and prints.

Among the objects of our invention is to provide a device of the above indicated character, simple in construction, easily manipulated and conveniently handled and which will maintain the sheets while under treatment constantly subjected to the action of the running water or other treating fluid 25 with the waving movement desirable in washing operations but contacting with the sheets over the least possible area consistent with maintaining the sheet substantially flat.

We attain this object broadly by mounting 30 each sheet loosely between a pair of flexible fine mesh screens carried in a portable carrier and subjecting the sheets to the action of a falling body of water directed edge-wise across the faces of the sheets in such 35 a manner as to cause the same to wave slightly and thus facilitate the washing and precipitating action of the water on the prints. The invention contemplates a washing and drying action even where there is no 40 apparent vibratory or waving motion of the sheets, the free access of the washing water or drying fluid to the entire face on both sides of the sheet being at the basis of the invention.

45 Various other objects and advantages of the invention will be in part obvious from an inspection of the accompanying drawings and in part will be more fully set forth in the following particular description of 50 one form of mechanism embodying our invention, and the invention also consists in certain new and novel features of construction and combination of parts hereinafter set forth and claimed.

Referring to the accompanying drawings: 55

Figure 1 is a side view of a washing tank with a loaded carrier therein and illustrating a preferred embodiment of our invention;

Figure 2 is a plan view of the device 60 closed in Figure 1;

Figure 3 is an end view in side elevation of a partially loaded carrier;

Figure 4 is a front view of the carrier 65 shown in Figure 3; and

Figure 5 is a transverse sectional view on the line 5—5 of Figure 3 showing a frame fastening means.

In the drawings there is shown a wash tank 10 which may be of any construction 70 best suited to receive the carriers herein-after described, and in this disclosure shown to be an open top rectangular box constructed of rolled copper plates or any other material which will not be affected by the chemicals 75 contained therein. The tank illustrated is of greater length than width and divided into four open top carrier receiving compartments 11 by means of the perforated and centrally intersecting partitions 12 and 13. The 80 top of the longitudinal partition 13 is outlined by a perforated spray pipe 14 designed to discharge washing fluid from opposite sides thereof into the four compartments. The spraying device is supplied from a pipe 85 15 leading from a water faucet or other source of water or liquid supply and controlled by means of a valve 16 designed to regulate the flow so as to attain a rate of flow best suited for the particular washing 90 or liquid treating operation involved. The intersecting partitions and the spray pipe 14 constitute a unit bodily movable from the tank to facilitate cleaning and the pipe 14 is connected to the supply pipe 15 by a 95 swiveled joint 17 so that the unit may be swung on this joint as a pivot without any necessity for breaking the water connection.

The bottom of each compartment is formed of a wide mouth funnel 18 leading to 100 a short discharge pipe 19. The four discharge pipes are suitably connected to a single main discharge 20 leading to a sewer connection or other suitable drain. The discharge pipe 20 is preferably provided with 105 some means for automatically maintaining a liquid level in the tank and for this purpose the pipe 20 is shown to be bent into an

L 21, which maintains the level indicated by the line *a—a*.

A tank of this character is designed to have a carrier 22 demountably positioned in each compartment for holding the sheets vertically and the detailed description of any one such carrier will be sufficient for all. The carrier is a book-form of open-work metallic trays provided with an upstanding handle. Described in detail, the carrier comprises a pair of vertically disposed end standards 23 preferably aluminum castings each including a relatively wide base portion 24 substantially triangular-shape in side elevation and continuous with a tall converging upright 25 topped by a laterally extending cylindrical boss 26 projecting inwardly. The center of the base portion 24 of each standard is provided with an opening 27 extending therethrough and outlined by an inwardly projecting cylindrical boss 28 with the axis thereof vertically disposed below the axis of the upper boss 26. The bosses of each standard are each connected by an inwardly projecting buttress web 29 so that the uprights are formed of T-shaped bars of gradually increasing cross-section of material from the upper towards the lower ends thereof. The base portions are provided with an inverted V-shaped line of pivot eyes 30 equally spaced and extending downwardly and outwardly towards opposite sides of the base from the vertical medial plane extending longitudinally through the device.

The side standards are connected adjacent their upper ends by means of a brace rod 31 preferably tubular with its opposite ends contained within the bosses 26 and suitably fastened thereto as by expanding the tube into the boss as shown to the left of Figure 2 or by means of a pin 32 passed laterally through the boss and tube as shown to the right of this figure. This upper brace constitutes a handle extending longitudinally of the tray and positioned in the said medial plane and above the center of gravity of the carrier when unloaded. The lower base portions of the standards are similarly connected by a tubular rod 33 fastened within the bosses 28 by machine screws 34. There is thus formed a braced skeleton frame with wide spreading supporting feet designed to fit within the compartments 11, free of bodily movement and of a height to bring the handle 31 adjacent the top of the tank when the carrier is positioned therein.

A plurality of sheet carrying frames 35 constituting, in effect, the leaves of the book-shaped carrier are pivotally mounted on opposite sides of the longitudinal medial plane and are each arranged to be moved from a horizontal loading position shown in dotted lines to the right of Figure 3 into the vertical stacked position shown in full lines in

this figure. The frames are formed of an outlining bar of rather heavy flat wire 36 bent to shape and preferably rectangular. Loosely stretched within this rectangular construction is a sheet of fine mesh metallic screen 37 preferably of 14-mesh fine round copper wires and of an interwoven character presenting to the sheet carried by and between the frames, spaced round points 38 or rather short lines rounded longitudinally and laterally of their lengths. This screen has been described as stretched loosely between the outlining frame but this is understood to mean that the screen is about as flexible as the screens in window screens in which the body of the screen as a whole is in one plane but sections thereof are bulged to form a somewhat irregular curved plane. As with the window devices the entire screen or at least the projecting portions of areas 85 thereof are capable of a slight movement perpendicular to the general plane.

Pivot pins 39 project from opposite ends of the bottom element of the rectangular bar 36 and extend into the pivot eyes on opposite standards so that each frame is pivotally connected at its lower edge to the standards. As the frames are of the same dimensions, and are pivoted to the inclined line of pivot eyes, the upper edges thereof will be stepped downwardly and outwardly so as to provide passageways, indicated by the arrows 41, leading under the upper outlining element 40 to the space between the screens even when each upper element of 100 each succeeding lower frame is engaging the side elements 42 of the next adjacent upper frame.

The frames are fastened in upright position by any suitable means, such as the 105 spring corrugated clips 44 secured to the standards by means of rivets 43, but it would be an obvious mechanical variation to fasten the innermost pair of frames to the web of the standards and clip each outer frame 110 to the adjacent inner frame.

In operation, the frames on one side of the trays are unfastened and laid horizontally on a support disposed adjacent the print discharge end of the photostat or in 115 other positions convenient to receive the wet sheets to be treated. The top frame is swung into vertical position and fastened in place. One or more sheets of films or prints, of an area sufficient to cover or substantially 120 cover the upper-face of the second frame is laid on top of this frame, preferably without overlapping and when the desired number of sheets are positioned on the frame, the same is raised and fastened to the first 125 frame with the sheet or sheets held vertically therebetween. Frame after frame is similarly covered and swung up into position until all the frames on one side are filled.

The carrier may then be lifted by the 130

handle and turned to present the frames on the other side to the loading operation as previously described.

The carrier with its frames raised and 5 fastened in position, is inserted into one of the compartments in the washing tank and is subjected to a bath of running water from the spray pipe. The parts of the tray are so proportioned that the sheets are below 10 the liquid level but all parts of the sheets are subjected to a vertically falling current of liquid which passes down on both sides of each sheet with little or no lateral movement and then passes into the bottom 15 funnel and through the trap into the drain.

As the spray pipe directs a layer of water to substantially all portions of the top surface of the bath and as the funnel bottom is positioned below the lower end of the 20 sheet carrying frames and opened directly thereto, substantially moving currents of water are set up in the bath. These currents pass across the faces of each sheet carrying with them the substances precipitated or 25 mechanically scoured from the emulsified side of the sheet accelerating the substances in their natural falling direction, but minimizing any tendency of the substances to be re-deposited on other portions of the sheet. 30 The currents have substantially the same velocity entirely across the faces of the sheets so that all portions of the faces are washed evenly, thus tending to eliminate discoloration due to unequal washing. The 35 upper ends of the stack of frames extend outwardly and downwardly so that there is formed an opening between the top element of each frame and the next adjacent inner frame in the screens thus providing a free 40 passage for the admission of water to the upper edges of the sheet. The construction described maintains the engaging screens spaced apart a distance greater than the thickness of the sheets thus permitting each 45 sheet to have some waving motion between the screens under the action of water passing across the faces of the same. This mechanical agitation of each separate sheet appears to facilitate the washing action. As the 50 screens are somewhat loosely mounted and in fact with screens of large area it is almost impossible to mount them otherwise, certain sections of this screen are bound to be warped out of their general plane and these 55 warped portions projecting towards the sheet constitute a means for holding the sheets lightly in their vertical positions.

As the sheets are free to move slightly or rather wave slightly under the action of the 60 body of the water passing edgewise across the faces thereof, the portion of the sheet engaging any of the raised portions of the screens, is moved away from the screen on the next wave and in this manner all portions of the sheet are at some time sub-

jected to the action of the water while out of contact with the screens. Even when a sheet is in engagement with the screens, there is only a relatively small aggregate area of the sheet in engagement therewith 70 as the high points of the screen are relatively small and well spaced apart leaving an aggregate open area practically equal to the area of the sheet continuously exposed to the action of the water. As these points are 75 rounded the actual point of contact is quite minute and this facilitates the formation of a thin film of water between the point and the adjacent portion of the sheet, so that, even when the sheet is in contact with the 80 screen there is maintained at all times a thin film of water held by the adhesion between the sheet and screen. In this way the sheets are held between cushioning films of water positioned to prevent actual contact 85 between sheet and screen but designed to prevent any possible curling of the edges of the sheet.

The sheets are allowed to remain in the bath of running water for a predetermined 90 period of time and with a rate of flow best adapted to attain a thorough washing, after which the carriers containing the washed sheets are bodily removed from the wash tank, allowed to drain for a moment and 95 the sheets are then subjected, while remaining mounted in the carriage, to the action of a current of air or other drying medium supplied thereto at a rate and in a drying condition best suited to dry the wet sheets. 100

The carriage is unloaded by lowering the frames successively and removing the dried sheets from between the screens. It will be found that the sheets treated by this method have been thoroughly washed in a relatively 105 short period of time, have dried in a flat or substantially flat condition and are ready to be mounted without the necessity of any ironing or other finishing operation to flatten or smooth the same.

By means of a device of this character the wet prints are handled with the least possibility of tearing the same. As they are maintained separated from each other they may be conveniently arranged in a definite 115 order. Each print may be tagged or otherwise identified and the operator thus knows just where any particular print may be during the cycle of washing and drying operations. Large wet sheets are difficult to 120 handle, but the horizontal disposition of the receiving frames facilitates the transferring of the sheet thereunto, for it is easier to move large wet sheets of paper horizontally through the air than to move them while 125 vertically disposed. The pivotal arrangement of the frame permits the sheets even those of large area to be swung into a vertical position thereby to take advantage of the vertically falling effect of the washing 130

water. There is no necessity for handling the sheets between the washing and drying steps as the open character of the carriage permits a free circulation of dry air across 5 and through the frames.

During the drying operation the frames may be slightly open relative to each other so as to facilitate the free passage of the drying air therebetween, care being taken 10 not to open the frame to an extent such as will permit the curling of the paper during the initial drying step. Positioning the pivot points at the lower end of the support and in a downwardly and outwardly inclined 15 line permits the frames to be stacked horizontally upon each other in their receiving position and at the same time minimizes any possibility of overturning the carrier. With the plates in their vertical position, the handle 20 is disposed above the center of gravity of the carrier, thus forming a conveniently handled basket for carrying the sheets from place to place.

While we have shown and described, and 25 have pointed out in the annexed claims, certain novel features of our invention, it will be understood that various omissions, substitutions and changes in the form and details of the device illustrated and in its operation may be made by those skilled in the 30 art without departing from the spirit of the invention.

Having thus described our invention, we claim:—

- 35 1. In a device of the class described, a washing tank provided with a compartment for containing a washing bath, perforated flexible means for positioning a flexible sheet to be washed vertically in said bath and 40 means for causing currents of liquid to pass in said bath vertically past all portions of said flexible sheet, said tank provided with an outlet below said sheet positioning means and spaced therefrom to form a compartment 45 for the liquid below the sheets whereby all portions of the sheet is subjected to a vertically falling sheet of liquid which drains off the entire lower edge of each sheet.
2. In a device of the class described, a 50 washing tank provided with a compartment for containing a washing bath, a pair of flexible perforated members adapted to be disposed relatively close together for loosely positioning a sheet to be washed vertically 55 in said bath, means for causing currents of liquid to pass in said bath vertically past all portions of said sheet, said compartment provided with an outlet spaced below said members to provide a drain space to insure 60 the vertical movement of the liquid across the lower portion of the sheet and means for automatically maintaining said bath at a definite level.
3. In a device of the class described, a 65 washing tank provided with a compartment

for containing a washing bath, a pair of flexible perforated members adapted to be disposed relatively close together for loosely positioning a sheet to be washed vertically in said bath, means for causing currents of liquid to pass in said bath vertically past all portions of said sheet, said compartment provided with an outlet spaced below said members to provide a drain space to insure the vertical movement of the liquid across 70 the lower portion of the sheet, means for automatically maintaining said bath at a definite level and means for controlling the rate of flow to said bath.

4. In a device of the class described, a 75 tank provided with a compartment for containing flat sheets positioned vertically therein, means for maintaining a liquid level in said compartment above the upper edge of said sheets and a supply pipe above 80 said level provided with a plurality of apertures for directing a liquid spray to the top of said bath and over a material area thereof, means for withdrawing the liquid from a material area of the bottom of the compartment along the entire length of the bottom edges of the sheets whereby substantially all portions of the sheets to be treated may be subjected to flat vertically falling currents of liquid.

5. In a device of the class described, a 90 wash tank provided with a partition for separating the tank into a plurality of compartments, a plurality of draining outlets, one from each of said compartments, a supply 100 pipe carried by and extending parallel to said partition and provided with apertures on each side for directing liquid into said compartment, said partition being removable as a unit from said tank to facilitate 105 cleaning.

6. In a device of the class described, the combination with a wash tank, of perforated flexible means spaced above the bottom of the tank for engaging a flexible sheet practically across its entire side for supporting the same vertically in said tank and means adjacent said first named means for directing streams of liquid vertically down across one face of said sheet whereby substances washed 110 from said sheet are carried in their precipitating direction and with a minimum length of travel in contact with the sheet and means for withdrawing the liquid from the bottom of the tank.

7. In a device of the class described, the combination of a wash tank, means for holding a flexible sheet against curling in a vertical plane but free to wave slightly in a direction transverse to its plane and means for 115 directing a fluid across one face of the sheet thereby to treat the same while subjecting the sheet to a slight waving motion.

8. In a device of the class described, means for supporting a sheet vertically and 120

for maintaining the same substantially flat, said means engaging the sheet by means of spaced apart rounded points aggregating a comparatively small area compared to the 5 total area of the sheet and means for subjecting the relatively large area between the points in contact with the sheet to the action of a liquid treatment.

9. In a device of the class described, a 10 pair of parallel substantially flat and slightly flexible sheets of fine mesh screens positioned relatively close to each other and adapted to contain a flexible sheet therebetween free to have slight movement in a direction perpendicular to the plane of the screens and means for subjecting the entire face on one side of said sheet to the action of a body of liquid moving across the same and simultaneously acting thereon to wave the sheet.

15 10. In a device of the class described, a pair of parallel substantially flat and slightly flexible sheets of fine mesh screens formed of fine round interwoven wires positioned relatively close to each other and 25 adapted to contain a flexible sheet therebetween free to have slight movement in a direction perpendicular to the plane of the screens and means for subjecting the entire face on one side of said sheet to the action 30 of a body of liquid moving across the same and simultaneously acting thereon to wave the sheet.

11. A book-form of carrier for handling 35 wet sheets comprising side supports and a plurality of frames pivoted at their lower ends between said supports whereby said frames will form superposed leaves adapted to be swung from a horizontal receiving position into a vertical stacked position and 40 means for fastening the frames in their raised position.

12. A book form of carrier for handling 45 wet sheets comprising a base portion and a pair of vertically disposed end standards extending upwardly from opposite ends of the base portion, a plurality of sheet carrying frames positioned between and having their lower edges pivotally supported in the end standards whereby each frame can be lowered 50 into a horizontal position or raised into a vertical stacked position and fastening means spaced from the pivoted edge of the frames and secured to the standards for securing any number of the vertical edges 55 of the frames to the adjacent standard on each end thereof.

13. A carrier comprising a pair of broad 60 bottom side supports, means connecting said supports adjacent their upper ends and means connecting said supports adjacent 65 their lower ends thereby to form an open-work frame, a plurality of sheet receiving members pivoted between said supports and on opposite sides of a horizontal vertical medial plane through the carrier, whereby

the members on one side will tend to counter-balance the members on the other side of the plane, said broad bottom of the side supports extending across said plane.

14. In a device of the class described, a 70 carrier including side supports, a plurality of sheet carrying frames pivotally mounted between said supports and adapted to be positioned vertically, the upper edge of each frame when in vertical position being positioned below the next adjacent inner frame whereby a fluid passageway is provided to the portion of each frame below its outlining upper edge.

15. In a device of the class described, a 80 carrier including side supports, a plurality of sheet carrying frames pivotally mounted between said supports and adapted to be positioned vertically, the upper edge of each frame when in vertical position being positioned below the next adjacent inner frame whereby a fluid passageway is provided to the portion of each frame below its outlining upper edge and means for holding said frames in position to maintain said passage- 85 way.

16. In a device of the class described, a 90 carrier including side supports, a plurality of sheet carrying frames pivotally mounted between said supports and adapted to be 95 positioned vertically, the upper edge of each frame when in vertical position being positioned below the next adjacent inner frame whereby a fluid passageway is provided to the portion of each frame below its outlining 100 upper edge, means for holding said frames in position to maintain said passageway and means for directing water through said passageways and between the several frames.

17. In a device of the class described, a 105 support, a plurality of frames carried thereby, each frame formed of an outlining member and a wire screen stretched within said member, said frames adapted to be positioned facing each other with a sheet disposed flatwise therebetween, said sheet and wire screen designed to have a slight play laterally of their general plane.

18. In a device of the class described, a 110 support, a plurality of frames carried thereby, each frame formed of an outlining member and a wire screen stretched within said member, said frames adapted to be positioned facing each other with a sheet disposed flatwise therebetween, said sheet and 115 wire screen designed to have a slight play laterally of their general plane and conveniently accessible means adjacent an outer edge of said frames for fastening the same 120 together in order.

19. In a device of the class described, a 125 support, a plurality of lapping frames each pivoted to said support and adapted to be swung from and to a vertical position, each frame including a sheet of slightly flexible 130

wire screen adapted to press lightly on a sheet carried between adjacent screens thereby to hold the sheet in vertical position.

20. In a device of the class described, 5 means for holding wet sheets in flat condition without injury to the faces of the sheet comprising a pair of wire screens imposed against each other and adapted to receive the sheet therebetween, said screens being 10 of fine interwoven mesh presenting spaced rounded points to the faces of the sheet and engaging the same over an aggregate area relatively small compared to the area of the sheet thereby to provide openings to the 15 faces of the sheet substantially equal in the aggregate to the entire area of the sheet.

21. In a device of the class described, means for holding wet sheets in flat condition without injury to the faces of the sheet comprising a pair of frames adapted to be 20 positioned facing each other with the sheet therebetween each of said frames including an outlining member of relatively great thickness and a fine mesh screen stretched within the outlining member constituting a 25 means tending to maintain the screens spaced from each other.

Signed at New York, in the county of New York and State of New York, this 6th day of July, A. D., 1915.

VERA F. LANGTON.
JAMES J. UNDERWOOD.
